UNITED STATES PATENT OFFICE.

ARTHUR W. WRIGHT, OF TRINIDAD, AND PHIL H. KNOWLTON, OF DENVER, COLORADO.

COMBINED WRITING-SHEET AND ENVELOP.

1,105,012.

Specification of Letters Patent.

Patented July 28, 1914.

Application filed April 2, 1913. Serial No. 758,448.

To all whom it may concern:

Be it known that we, ARTHUR W. WRIGHT, a citizen of the United States, residing at Trinidad, in the county of Las Animas, State of Colorado, and PHIL H. KNOWLTON, a citizen of the United States, residing at Denver, in the county of Denver and State of Colorado, have invented certain new and useful Improvements in Combined Writing-Sheets and Envelops, of which the following is a specification.

Our invention relates to a combined writing sheet and envelop and its primary object resides in the provision of a sheet of writing paper which may be conveniently folded and sealed for its transmission by mail and which is provided with means for the transference of the name and address of the addressee when written so as to appear upon the outside of the folded article for the direction of the postal officials, onto the writing sheet at the head of the communication or other matter written or imprinted upon the inner surface thereof.

By the use of our invention the mistakes which often occur in copying the name and address from a statement or letter onto the envelop in which the same is to be inclosed, the time and labor are effectively avoided, the time and labor involved in separately addressing the envelops and their inclosures, are eliminated and the cost of production is materially reduced when compared with that required in providing the separate envelops and writing sheets at present in common use.

An embodiment of our invention has been illustrated in the accompanying drawings in the various views of which like parts are similarly designated and in which,

Figure 1, represents a blank statement-sheet formed in accordance with our invention, in the flat or unfolded condition, Fig. 2, a similar view of the same with the sealing flap folded in the position it occupies while the name and address of the addressee and other matter are being written on the sheet, Fig. 3, a similar view of the sheet illustrating the first step employed in folding it for its transmission by mail, Fig. 4, a view of the article after the second step in the process of folding the same has been completed, Fig. 5, a face view of the combined writing sheet and envelop in the folded and sealed condition, Fig. 6, a reverse view of the same, Fig. 7, a face view

of a modification of the form of our invention shown in Fig. 1, in the unfolded condition, and Fig. 8, a similar view of still another modification in the construction of our invention.

Referring first to Figs. 1 to 6 of the drawings, the reference numeral 2 designates the writing sheet which in the illustration, has been ruled for use as a statement of an account, and which by scored, weakened or otherwise established folding lines 3, is divided into a central body-section 4 and two wing-sections 5. The numeral 6 designates the sealing flap of the article which is formed at the upper edge of the sheet 2 upon which it may be folded along a line 7 coincident with the said edge. The flap 6 whose side edges extend in alinement with the above-mentioned folding lines 3, is provided at its outer corners with laterally projecting ears 8, the inner surfaces of which are coated with an adhesive substance as indicated by broken line shading as at 9, for the purpose of sealing the letter or statement as will hereinafter be more fully described. The adhesive substance is furthermore applied on the inner surface of the flap along its outer edge as shown by similar shading at 10 and another portion of the same surface is coated as at 12 with a carbon solution or other preparation suitable to produce a transfer of matter written or imprinted on the outside of the flap, upon the surface upon which the same is folded.

In using our improved writing sheet, the sealing flap is first of all folded upon the sheet 2 along the line 7 after which the name and address of the addressee is written upon the outer surface of the same as shown at 13 in Fig. 2, and the statement of the account or other communication is at the same time written or imprinted upon the surface of the sheet below the flap. The writing on the flap is by reason of the carbonization of its inner surface, reproduced on the sheet at the head of the matter written thereon as illustrated at 14, Fig. 1, and after the flap has been returned to its original position the article is ready to be folded and sealed for its transmission by mail or other method of transportation. To fold the letter for the last mentioned purpose the wings 5 are folded along the line 3 upon the intermediate body portion as shown in Fig. 3, after which the sheet is doubled as shown in Fig. 4 110

along a transverse folding line which in Figs. 1 and 3 is indicated by the broken line 15. The flap is now again folded along the line 7 but this time upon the outer surface 5 of the folded sheet to which it is subsequently secured by moistening the adhesive applied along its outer edge, and as a final step in the process of sealing the missive, the ears 8 are turned around the edges of 10 the folded article and secured upon the back thereof by moistening the adhesive coating applied at their inner surfaces. The article thus being folded and sealed as illustrated in Figs. 5 and 6 is now ready for delivery, 15 the address written upon the flap appearing upon the face of the same as is shown in Fig. 5 and it may be readily opened by the addressee by drawing a knife or paper cutter between the folded flap and the sheet, where- 20 by the two parts are severed along the line 7, about which the flap was folded.

The modified form illustrated in Fig. 7 differs from that hereinabove described only in that the ears on the flap have been 25 omitted, and the form shown in Fig. 8 differs from the others in that the writing sheet 2 is made of larger size and is thus better adapted for writing letters or printing circulars. In this form the sheet is after the 30 wings have been folded thereon along the longitudinal lines 3, twice folded along the transverse lines 16 which divide the sheet in three parts of equal width.

Having thus described our invention what

we claim and desire to secure by Letters- 35 Patent is:

As a new article of manufacture, a combined writing sheet and envelop comprising a sheet and a sealing flap which when folded upon the sheet along a determinate line coincident with the upper edge of the same, covers the upper portion of the inner or writing surface of the sheet and which when folded along the said line after the sheet is folded upon itself along a determinate line, 40 engages the outer surface of the same, the said sheet being capable of being folded along a transverse line and the said flap having means for its attachment to the said outer surface of the sheet, and, upon its 45 inner surface, a coating of transfer material for the production of an impression of matter written upon its outer surface, upon the upper portion of the inner surface of the sheet, which it covers when it is folded along 50 its said folding line, prior to the folding of the sheet upon itself.

In testimony whereof we have affixed our signatures in presence of two witnesses.

ARTHUR W. WRIGHT.
PHIL H. KNOWLTON.
